CLAIM

The ornamental design for a wheel hub cover for industrial vehicles, as shown and described.

DESCRIPTION

FIG. 1 is a perspective view of a wheel hub cover for industrial vehicles showing my new design;
FIG. 2 is a front elevational view thereof;
FIG. 3 is a bottom plan view thereof, with the top plan view being a mirror image;
FIG. 4 is a left side view thereof, with the right side view being a mirror image; and,
FIG. 5 is a rear elevational view thereof.
The cross-hatch lining which appears throughout the drawing disclosure represents conventional stitching.
